JOHN C. ANDERSON, OF KEYPORT, NEW JERSEY

CONVEYER BELT ELEMENT FORMING MACHINE

Application filed March 23, 1932. Serial No. 600,602.

This invention relates to a device for forming wire coils of the type which when assembled together form a conveyer belt, such for example as those used in glassware annealing for conveying the glass articles to be annealed through the tunnel type annealing lehrs. The use of such belts is generally illustrated in the Mulholland Patent 1,560,481, granted Nov. 3, 1925. The particular belt formed of the coil which is illustrated as being made by the machine shown in the accompanying drawing and described hereinafter, however, forms the subject matter of my copending application, Serial No. 15 600,603, filed Mar. 23, 1932, the present invention being confined to the machine by which coils of wire for this novel belt or other types of wire coils may be made.

Among the objects of the present invention are to provide a simple, cheap and effective device by which wire coils for conveyer belts or other uses may be easily and cheaply made.

A further and more specific object of the invention is to provide in a machine of the character described a means for forming at least one, and in the illustrated embodiment of the invention, two portions of each turn of the wire forming the coil into a peculiar predetermined configuration, such means including an abutment means and one or more positively operated pusher members by which the desired predetermined shape may be imparted to the portion or portions of the wire coil being made.

A further object of the present invention is to provide in a device of the character described a simple and effective means by which the pitch of wire coils being formed may be adjustably determined.

Other and more specific objects of the invention will become apparent from a reading of the following specification and subjoined claims when taken in connection with the accompanying drawing, in which:

Figure 1 is a plan view of the device;

Fig. 2 is a front elevation of the device of Fig. 1 with parts broken away and in 50 vertical section;

Fig. 3 is an end elevation as seen from the left of Figs. 1 and 2; and

Fig. 4 is a fragmentary view of a portion of a conveyer belt made up of coils formed by the machine shown in Figs. 1 to 3. 55

As shown in the accompanying drawing, the machine comprises a base 1 upon which is a standard 2 which may be integral therewith and which carries a bearing for a shaft 3 which in turn carries a mandrel 4, the mandrel being secured thereto in any suitable manner as by the countersunk rivets 5. As shown the mandrel is tapered toward its free end (the left as seen in Figs. 1 and 2) to provide clearance at the end from which the coil is removed as it is formed. The shaft 3 and consequently the mandrel 4 carried rigidly thereby are adapted to be driven in the direction of the arrows by any suitable power means (not shown). Wire from any suitable supply is conducted to the machine, as illustrated at 6, it being assumed that the wire is maintained under the proper tension by any desired means which may be of well-known character. Thus as the mandrel 4 is rotated in the direction of the arrows in the several figures, the wire will be wound thereon. 70

Suitably secured to the base 1, as by bolts 7, is a standard 8 which carries a pivot pin 9 for an abutment member 10 which cooperates with the wire being wound upon the mandrel 4. The abutment 10 is continuously urged to move about its pivot toward the mandrel by a suitable resilient means, here illustrated as a tension spring 11, extending between a pin 12 fixed to the abutment member 10 at its upper end and a suitable anchorage, here illustrated as a hook 13, at its lower end. 75

The mandrel 4 is shaped according to the form of coil to be made and as shown is flattened on each side in order to make a flattened coil. In the event that any non-circular mandrel is used, it is necessary that the abutment member 10 have a movement substantially as shown in order that it may cooperate at all times with the mandrel and contact at all times with at least a part of each turn of the wire being wound thereon. This movement need not be pivotal as illustrated, 85 90 95 100

however. The abutment member 10 is provided with a recessed portion 14 as illustrated, in order that it may contact with the mandrel 4 at all times and particularly upon 5 the initial turning over of the mandrel, and prior to the action of the pusher, later to be described, and not interfere with the last made coil portion.

In order to push the formed coil of wire 10 outwardly along the mandrel and also to form portions thereof into predetermined shape against the abutment 10, there is provided one or more pushers rotatable with the mandrel, in the present instance two being 15 shown, cooperable respectively with the flattened sides of the mandrel 4 in order to form the coil shown in the instant drawing. The form of abutment and pusher members illustrated are such that the portions of each turn 20 lying along the flattened sides of the mandrel will be perpendicular to a plane containing the axis of rotation of the mandrel, although other forms may be made by using a suitably shaped abutment member and complementary shaped pusher member or members. The form of coil made by the device 25 illustrated, and consequently of conveyer belt, is illustrated in Fig. 4, although it is to be understood that the present invention is 30 not limited in its utility to the formation of this type only of wire coil. As illustrated in the accompanying drawing, the shaft 3 is provided with a pair of flattened faces 15 and 16 parallel to its axis of rotation. Pusher 35 members 17 and 18 are arranged against these faces for longitudinal sliding movement with respect to the shaft 3. As illustrated (Fig. 2) the left hand or operating ends of the pusher members 17 and 18 are turned inwardly or 40 formed with inward projections extending toward the axis of rotation of the shaft 3 and into sliding engagement with the flattened faces of the mandrel 4, the inner ends of these projections being suitably shaped to 45 cooperate with the abutment member 10 to engage between these parts the last portion 19 of the turn of wire being formed so that this portion 19 will be engaged between the lower end of one of the pushers, in this case 50 the pusher 17, and the lower edge of the abutment member 10. The pushers 17 and 18 are held in place upon the shaft 3 by a suitable sleeve-like member 20 which surrounds the narrowed and squared end portion of the 55 shaft 3, and also the pusher members 17 and 18, and is secured in position by a cross pin 21, which may be riveted, threaded or keyed in place to hold the parts in assembled relation. 60 At their ends opposite the active pushing ends (the right hand ends as seen in Figs. 1 and 2), the pusher members 17 and 18 are provided with sector cams 22 and 23 respectively which may be integral therewith. Co- 65 operable with both these cams is a roller 24

mounted upon a vertically disposed pintle 25 secured in a bracket 26, which may be suitably secured as by a bolt 27 to the standard 70 2. Thus, as the shaft 3 is rotated in the direction of the arrows, the inclined cam surface 28 of the cam sector 22 will be engaged by the roller 24 forcing the pusher 17 to the left, as seen in Figs. 1 and 2, the first movement being operative to force the formed coil of wire outwardly along the mandrel a distance equal to half the pitch of the wire, and continued movement being effective to form the portion 19 of the wire into the desired configuration by squeezing it between the end 75 of the pusher 17 and the abutment 10. Thereafter, and for a material portion of the rotation of the mandrel 4, the pusher 17 will be maintained in its forward position by the cooperation of the roller 24 with the flat face 29 of the cam 22, the face 29 lying in a plane 80 perpendicular to the axis of rotation of the shaft 3. During this time the abutment 10 will be at all times in engagement with the mandrel 4, and also with the wire being wound thereon at some place, although this 85 engagement may be with but a small part of the wire. Also during this time the abutment 10 will be moved in a counterclockwise direction about its pivot pin 9, as seen in Fig. 3, due to the rotation of the mandrel 4 and the 90 non-circular configuration thereof. As the next flattened face of the mandrel 4 is brought toward the uppermost position, and the pusher 18 approaches its top position, the abutment 10 will be moved clockwise, as seen 95 in Fig. 3, by the spring 11.

In order to retract the pusher members 17 and 18 there are provided resilient means comprising compression springs 30 and 31 disposed in suitable bores or recesses in the 100 sleeve-like member 20 and bearing against the sector cam portions 22 and 23 of the pushers 17 and 18 respectively.

In order adjustably to determine the pitch of the wire, there is provided a wire guiding bracket 32 against one vertical face 33 of which the wire passes. This bracket is adjustably secured to the base 1 in any desired manner as by providing the horizontal web 105 of the bracket with elongate slots 34, through which bolts 35 may pass, the bolts being threaded into the base 1. Thus, as each part 110 of each turn of wire is formed by the conjoint action of the pusher 17 or 18 and the abutment 10, the wire is given an angular bend toward the direction of its axis, as illustrated in Figs. 1 and 2, so that due to 115 the continued rotation of the mandrel 4, the coil will be formed in desired shape as shown. Inasmuch as the pushers are always moved outward to the same position, the position 120 of the bracket member 32 will determine the pitch of the coil being formed, this being adjustable by properly adjusting the bracket 125 32 with respect to the base 1, which may be 130

accomplished by loosening the bolts 35, setting the bracket to the desired position, and again tightening the bolts.

The coils formed on the machine of Figs. 5 1 to 3, may be suitably threaded together to make a continuous conveyer belt, as illustrated in Fig. 4, wherein a plurality of these coils 36 are shown in their normal relation in a belt. The ends of the coils may be suit- 10 ably joined by twisting the ends of the wire together, as illustrated at 37. Inasmuch, however, as the particular belt here shown forms the subject matter of my copending application above referred to, details of the 15 belt and its advantages in use will not be given herein, it being understood that the present device is adaptable for forming wire coils of different configurations which may be used for various purposes, among which 20 is that of forming conveyer belts for glass annealing lehrs.

Also while I have shown a machine for making wire coils having a right hand twist or pitch, it will be understood that coils having a left hand wound twist or pitch may be made upon a similar machine including corresponding elements and the same manner of operation.

While I have shown and described but one 30 embodiment of my invention, it will be understood that various changes may be made therein and various features may have individual utility in other combinations. I do not wish to be limited, therefore, except by the 35 scope of the appended claims, which are to be construed as broadly as the state of the prior art permits.

I claim:

1. Apparatus for forming a wire coil for 40 a conveyer belt, comprising a rotary mandrel, means for supporting said mandrel for rotation, an abutment means cooperating with said mandrel, and means movable in a direction substantially parallel to the axis of rotation of said mandrel and cooperating with said abutment means to shape at least a part of each turn of the wire coil to a predetermined form on said mandrel.

2. Apparatus for forming a wire coil for 50 a conveyer belt, comprising a rotary mandrel upon which the wire is adapted to be wound, means for supporting said mandrel for rotation, an abutment means cooperating with said mandrel, means movable in a direction substantially parallel to the axis of rotation of said mandrel and cooperating with said abutment means to shape therebetween at least a part of each turn of the coil to a predetermined form on said mandrel, and means for adjustably determining the pitch of the coil being formed.

3. Apparatus for forming a wire coil for 60 a conveyer belt, comprising a rotary mandrel about which the wire is adapted to be coiled, means supporting said mandrel for rotation,

abutment means not partaking of the rotation of said mandrel but cooperating therewith, and a cam operated pusher member mounted to rotate with said mandrel and cooperating with said abutment means to shape 70 at least a portion of each turn of the coil being formed to a predetermined shape by movement in a direction parallel to the axis of rotation of said mandrel.

4. Apparatus for forming a wire coil for 75 a conveyer belt, comprising a rotary mandrel upon which the wire is adapted to be coiled, means mounting said mandrel for rotation about a fixed axis, abutment means not partaking of the rotation of said mandrel but 80 cooperating therewith and continuously contacting with the wire being coiled therealong, a cam operated pusher member mounted for rotation with said mandrel and also for movement in a direction parallel to its axis of rotation for periodically engaging the wire being 85 formed into the coil to shape at least a portion of each turn thereof to a predetermined form, and means for adjustably determining the pitch of the coil being formed.

5. Apparatus for forming a wire coil for a 90 conveyer belt, comprising a mandrel flattened on opposite sides about which the coil is adapted to be wound, means for supporting the mandrel for rotation about a fixed axis, 95 abutment means for continuously engaging the wire on said mandrel but not partaking of the rotation thereof, pusher means mounted for rotation with said mandrel and also adapted for movement in a direction parallel 100 to the axis of rotation thereof, and means for moving said pusher means in a direction parallel to the axis of the rotation of the mandrel to force portions of the wire against said abutment means, whereby to form at least a 105 part of each turn of the wire into a predetermined form.

6. Apparatus for forming a wire coil for a 110 conveyer belt, comprising a mandrel having at least one flattened side, means for mounting said mandrel for rotation about a fixed axis, an abutment member for engaging the wire being coiled upon said mandrel, means for mounting said abutment member for movement in a direction substantially per- 115 pendicular to the axis of rotation of said mandrel, means for resiliently urging said abutment member against said mandrel, pusher means cooperating with said mandrel and 120 said abutment member to form at least a portion of each turn of the coil being made into a predetermined shape, means for mounting said pusher member with rotation with said mandrel and also for movement in a direction 125 parallel to the axis of rotation thereof, and means for periodically moving said pusher member in a direction parallel to the axis of rotation of said mandrel to engage a portion of the coil opposite said abutment member 130 and thereby to shape such portion of each

turn of the coil into a predetermined form.

7. Apparatus for forming a wire coil for a conveyer belt, comprising a mandrel having at least one flattened side, means for mounting said mandrel for rotation about a fixed axis, an abutment member for engaging the wire being coiled upon said mandrel, means for mounting said abutment member for movement in a direction substantially perpendicular to the axis of rotation of said mandrel, means for resiliently urging said abutment member against said mandrel, pusher means cooperating with said mandrel and said abutment member to form at least a portion of each turn of the coil being made into a predetermined shape, means for mounting said pusher means for rotation with said mandrel and also for movement in a direction parallel to the axis of rotation thereof, a cam portion rigid with said pusher means, a fixed roller cooperating with said cam portion positively to force said pusher means toward said abutment member to shape a portion of each turn of the coil being formed between said pusher means and said abutment member, and resilient means for moving said pusher means in the opposite direction to move said cam portion toward and against said roller.

- 30 8. Apparatus for forming a wire coil for a conveyer belt, comprising a mandrel having at least one flattened side, means for mounting said mandrel for rotation about a fixed axis, abutment means continuously engaging the wire being coiled upon said mandrel, means for mounting said abutment means for movement in a direction substantially perpendicular to the axis of rotation of said mandrel, resilient means for urging said abutment means toward said mandrel, pusher means cooperating with the flattened side of said mandrel, means for supporting said pusher means for rotation with said mandrel and also for movement in a direction parallel to the axis of rotation of said mandrel, resilient means for moving said pusher means in a direction away from the wire being coiled upon said mandrel, positive means for positively moving said pusher means toward the wire being coiled upon said mandrel to force a portion of the wire on the flattened side of said mandrel toward said abutment means and thereby to form it into a predetermined shape, and means for adjustably determining the pitch of the coil of wire being formed.

- 60 9. Apparatus for forming a wire coil for a conveyer belt, comprising a mandrel flattened on opposite sides about which the wire is to be coiled, means for mounting said mandrel for rotation about a fixed axis, an abutment member cooperating with said mandrel and adapted at all times to be in engagement with a portion of the wire being coiled thereon, pivot means for mounting said abutment

for movement about an axis spaced from but parallel to the axis of rotation of said mandrel, resilient means for urging said abutment member against said mandrel, a pair of pusher members for feeding the formed coils along and off said mandrel and for forming shaped portions of said coil against said abutment member, means for mounting said pusher members for rotation with said mandrel and also for movement in directions parallel to the axis of rotation thereof, resilient means for moving each of said pusher members in a direction away from the coil of wire being formed on said mandrel, cam sectors formed rigid with each of said pusher members, and a fixed cam roller for engaging said cam sectors consecutively to form two portions of each turn of said coil into predetermined shapes against said abutment member and also to move said coil along said mandrel as it is formed, and a wire guiding means fixedly but adjustably positioned adjacent to said mandrel for adjustably determining the pitch of the coil of wire being formed.

Signed at Keyport, N. J., this 11th day of March, 1932.

JOHN C. ANDERSON.
